CLAIM

The ornamental design for a terminal metal fitting for electrical connector, as shown and described.

DESCRIPTION

FIG. 1 is a front, top and right side perspective view of a terminal metal fitting for electrical connector showing my new design;

FIG. 2 is a front view thereof;

FIG. 3 is a rear view thereof;

FIG. 4 is a top plan view thereof;

FIG. 5 is a bottom plan view thereof;

FIG. 6 is a right side view thereof;

FIG. 7 is a left side view thereof;

FIG. 8 is a cross-sectional view taken along line 8-8 in FIG. 6; and,

FIG. 9 is a cross-sectional view taken along line 9-9 in FIG. 6.

The broken lines illustrate portions of the terminal metal fitting for electrical connector and form no part of the claimed design. The dash-dotted lines denote the boundary of the claim and form no part of the claimed design.
